MATERNITY GIRDLE

Raymond P. Bonang, 5 Calef Ave., Saco, Maine
Filed Sept. 18, 1964, Ser. No. 397,566
8 Claims. (Cl. 128—579)

This invention relates to maternity girdles and consists more particularly in new and useful improvements in a maternity girdle having an abdomen supporting pouch which is held in position on the wearer by a harness assembly consisting of a continuous strap so designed and secured to the pouch as to uniformly support the upper and lower extremities of the latter when criss-crossed over the shoulders and back of the wearer, thus providing a counteracting abdominal support. In other words, the pouch does not go slack or release its support in any position of the wearer and provides a continuous uplifting action which affords more freedom and comfort to the wearer.

Heretofore, various types of maternity girdles have been designed, but in all instances with which I am familiar, these prior devices have relied upon shoulder straps as their sole supporting means. Furthermore, the multiple straps of these prior girdles have not only been awkward to adjust and connect, but no attempt has been made to support the abdomen from both the upper front or top portion and the lower area. An additional objection to known maternity girdles has been the fact that in most instances they have employed straps or harnesses which pass through the crotch and between the wearer's legs, thus causing irritation and binding, which naturally leads to considerable discomfort.

It is therefore the primary object of the present invention to provide a maternity girdle having a pouch portion formed of a series of triangular shaped pieces of cloth designed and connected to conform substantially to the contour of the abdomen and supported in such a manner as to afford a continuous uplifting support by means of a continuous supporting strap or harness assembly which is connected to the pouch in such a manner as to give uniform and continuous support to both the upper and lower regions of the abdomen.

Another object of the invention is to provide a maternity girdle which is effective in relieving backstrain in pregnant women, as well as general fatigue.

Still another object of the invention is to provide an improved maternity girdle which will minimize stretch marks on the body of pregnant women.

A further object of the invention resides in the provision of a maternity girdle which eliminates the use of crotch-engaging straps to thus eliminate irritation and binding.

A still further object is to provide a maternity girdle which does not require snaps, buckles or hooks for securing it in place.

With the above and other objects in view which will appear as the description proceeds, the invention consists in the novel features herein set forth, illustrated in the accompanying drawings, and more particularly pointed out in the appended claims.

Referring to the drawings in which numerals of like character designate similar parts throughout the several views:

FIG. 1 is an elevational view of the girdle of the present invention in open position, illustrating the continuous strap arrangement as viewed from the rear face of the girdle;

FIG. 2 is a front elevational view showing the girdle in place on a wearer;

FIG. 3 is a similar view in side elevation; and

FIG. 4 is a fragmentary rear view of the supporting harness.

In the drawings, it will be seen that the girdle comprises an abdominal support or pouch, generally indicated at 5, which is formed of a plurality of substantially triangular segments 5a-5f, shaped and sewn together along 5 adjacent edges in a manner to conform substantially to the contour of the wearer's pendulous abdomen. These segments may be composed of any suitable cloth and elastic material is not required, due to the conforming shape of the overall pouch. While the drawings show 10 six segments or panels, it will be understood that this is purely for purposes of illustration, and the number of panels may be varied to suit varying conditions.

The end pouch panels 5a and 5f are tapered at their longitudinal extremities to which are respectively secured 15 overlapping waist bands 6 and 7, and, preferably, at the points of connection to the pouch, elastic inserts 8 are incorporated to accommodate the stretch points when the girdle is in place. Toward their respective ends, the waist bands 6 and 7 are preferably provided with pairs 20 of coacting strips 6a and 7a, of a material which is sold commercially under the trade name "Velcro." These strips are sewn on opposite sides of the respective waist bands so that when the latter encircle the waist of the wearer in the desired position of adjustment, the Velcro strip 6a overlaps and contacts the strip 7a, as shown in FIG. 4, and they are joined with a clinging effect through coaction of the engaging surfaces of the strips, a function for which "Velcro" is especially designed. Thus, proper adjustment and fastening may be accomplished 25 without the use of buckles, snaps, clasps, etc.

Extending across the lower boundary of the pouch 30 5 and suitably stitched to the front face thereof is the main supporting strap 9 of the harness assembly. Preferably, the intermediate portion of this main strap is stitched as at 10 to the adjacent lower extremities of the intermediate front panels 5b, 5c, 5d and 5e, the unstitched ends of the strap freely overlying the side pouch panels 5a and 5f. Opposite free ends of the strap 9 respectively terminates in shoulder strap extensions 11 and 12, designed to pass over the back and shoulders of the wearer and criss-cross at the back, as best seen in FIGS. 1 and 4. The shoulder strap extensions 11 and 12 are 35 of reduced width and their ends are adapted to be looped through flattened metal or plastic rings 13 and 14 carried 40 at the upper extremities of spaced elastic connecting strips 15 and 16, which are preferably secured to pouch panels 5b and 5e respectively. After being passed through the rings 13 and 14, the ends of the respective shoulder straps 11 and 12 are folded upwardly upon themselves as at 45 11a and 12a (FIG. 2) and secured in the proper adjusted lengths by coacting "Velcro" strips 11b, 11c, 12b and 12c 50 in a manner similar to the coacting strips 6a and 7a on the waist bands just described.

It will thus be seen that when the girdle is properly 55 adjusted on the wearer with the pouch 5 closely conforming to the abdomen, the main supporting strip 9 and its shoulder and backstrap extensions 11 and 12 provide a continuous, counteracting supporting structure designed to afford uplifting support both across the lower front 60 portion of the pouch and abdomen and across the upper edge of the pouch. The elastic inserts 8 and elastic connecting strips 15 and 16 absorb and adjust any uneven tensions which may be felt by the wearer from the pull at the top of the stomach as compared with the pull from 65 the bottom of the abdomen. Equal tension is exerted throughout the entire maternity girdle when the waistband and supporting straps are properly adjusted.

Furthermore, due to the "Velcro" strips 6a, 7a, 11b, 11c, 12b and 12c, the girdle is easily secured and readily 70 adjustable without the use of snaps, buttons or hooks of any kind.

The maternity girdle of the present invention is far more simple in design and construction than those heretofore known, and it embodies a novel principle not contemplated in prior constructions, namely, the employment of counter-supporting action. In other words, the tensions are such that if the wearer bends forward, there will be no loss of support to the abdomen, and should the wearer bend her shoulders backwards, the tensions will be transferred over to the front straps with a lifting action which will afford no loss of tension to the abdomen.

From the foregoing, it is believed that the invention may be readily understood by those skilled in the art without further description, it being borne in mind that numerous changes may be made in the details disclosed without departing from the spirit of the invention as set forth in the following claims.

I claim:

1. A maternity girdle comprising an abdominal pouch contoured to embrace the abdomen of a wearer, said pouch terminating at its opposite longitudinal extremities in waist encircling bands, means for adjustably connecting the ends of said bands over the back of the wearer, a supporting harness consisting of a continuous strap, the central longitudinal area of which extends across and is secured to the central lower boundary of said pouch, the opposite longitudinal extremities of said strap beyond said central area being free from said pouch and respectively terminating in elongated shoulder strap extensions which are directed diagonally upward to partially overlie the adjacent portions of said pouch and adapted to criss-cross over the back and pass forwardly and downwardly over the shoulders of the wearer, and means for adjustably securing the free ends of said criss-crossed extensions at spaced points along the upper longitudinal boundary of said pouch, whereby continuous and uniform support is provided for the abdomen along both the upper and lower extremities of said pouch.

2. A maternity girdle comprising an abdominal pouch contoured to embrace the abdomen of a wearer, said pouch terminating at its opposite longitudinal extremities in waist encircling bands, means for adjustably connecting the ends of said bands over the back of the wearer, a supporting harness engageable solely with portions of the wearer's body located above the crotch, said harness consisting of a continuous strap, the central longitudinal area of which extends across and is secured to the central lower boundary of said pouch, the opposite longitudinal extremities of said strap beyond said central area being free from said pouch and respectively terminating in elongated shoulder strap extensions which are directed diagonally upward to partially overlie the adjacent portions of said pouch and adapted to cross-cross over the

back and pass forwardly and downwardly over the shoulders of the wearer, and means for adjustably securing the free ends of said cross-crossed extensions at spaced points along the upper longitudinal boundary of said pouch, whereby continuous and uniform support is provided for the abdomen along both the upper and lower extremities of said pouch.

5 3. A maternity girdle as claimed in claim 1, wherein said waistbands are provided with elastic inserts and said shoulder strap extensions are connected to the upper boundary of said pouch by elastic means.

10 4. A maternity girdle as claimed in claim 1, wherein said pouch is formed of a series of substantially triangular cloth panels converging at their lower ends and 15 stitched together along adjacent edges.

5 5. A maternity girdle as claimed in claim 1, wherein the upper edge of said pouch is provided with upwardly extending, elastic connecting straps, rigid rings carried 20 at the upper extremities of respective elastic straps through which the free ends of said shoulder straps are adapted to be looped, and adjustable means on said shoulder straps for securing them in looped condition.

25 6. A maternity girdle comprising an abdominal pouch contoured to embrace the abdomen of a wearer, a waistband for securing said pouch in place, an integral supporting strap, the central longitudinal area of which extends across and is secured to the central lower boundary of said pouch, the opposite longitudinal extremities of said strap forming shoulder engaging extensions directed 30 diagonally upward and adapted to criss-cross over the back and pass forwardly and downwardly over the shoulders of the wearer, and means for adjustably securing the free ends of respective shoulder extensions to the upper boundary of said pouch on opposite sides of the latter.

35 7. A maternity girdle as claimed in claim 6, wherein the upper boundary of said pouch is provided at longitudinally spaced points with elastic connecting straps, rigid rings carried by said connecting straps through which the free ends of respective shoulder extensions are 40 adapted to be looped, and means for adjustably securing said shoulder extensions in looped condition.

45 8. A maternity girdle as claimed in claim 7, wherein said last-named means comprise coacting "Velcro" strips secured on opposite surfaces of respective shoulder extension.
